(57) **CLAIM**

The ornamental designs for time-measuring instrument, as shown and described.

DESCRIPTION

FIG. 1 is a perspective view of my design for a time-measuring instrument;

FIG. 2 is a front orthogonal view of my design;

FIG. 3 is a right side orthogonal view of my design;

FIG. 4 is a left side orthogonal view of my design; and,

FIG. 5 is a bottom orthogonal view of my design, the top orthogonal view being a mirror image thereof.

The dashed lines in FIGS. 1-5 represent a wristband and form no part of the claimed design.
